UNITED STATES PATENT OFFICE.

FLOYD BISCH, OF PHILADELPHIA, PENNSYLVANIA.

COMBINED SIGNAL AND LICENSE DISPLAY DEVICE.

Application filed January 26, 1922. Serial No. 531,832.

To all whom it may concern:

Be it known that I, FLOYD BISCH, a citizen of the United States, residing at Philadelphia, in the county of Philadelphia and State of Pennsylvania, have invented certain new and useful Improvements in Combined Signal and License Display Devices, of which the following is a specification.

One object of my invention is to provide improved means which can be used on vehicles for the purpose of displaying an illuminated signal showing the intention of the driver to stop; said means also including a portion having a license tag located therein and arranged to be illuminated to clearly show the markings thereon and the color representative of the year coloring of the license.

Another object is to make an extremely simple arrangement of the parts and so that they cannot be tampered with by an unauthorized person.

These objects, and other advantageous ends which will be described hereinafter, I attain in the following manner, reference being had to the accompanying drawings in which—

Figure 1 is a face view of a device made in accordance with my invention,

Figure 2 is a sectional plan view taken on the line 2—2 of Figure 1,

Figure 3 is a sectional elevation taken on the line 3—3 of Figure 1,

Figure 4 is a sectional view taken on the line 4—4 of Figure 3,

Figure 5 is a fragmentary view showing a portion of one end of the device, and

Figure 6 is a fragmentary sectional view taken on the line 6—6 of Figure 3.

Referring to the drawings, my improved device includes a case 7 which is preferably made of cast metal and includes a rectangular box portion 8. One end 9 of the box portion 8 has an opening 10 and at the front and rear of said opening and at the top are provided ribs 11 which are spaced apart to provide a channel 12 for a gate 13. This gate consists of a plate adapted to be slid upward through the channel 12 and has an angular flange 14 provided with a hole 15 to register with an eye lug 16 which is cast integral with the bottom 17 of the box portion 8 so that when the gate is raised into a position closing the opening 10, the eye lug

16 will extend through the hole 15 and a lock, such as the lock 17^a illustrated in Figure 1, can be inserted through the eye lug 16 and thus lock the gate in its closed position.

The box portion 8 is elongated transversely so that when the gate 13 is removed a license tag 18 can be slid into the box portion through the opening 10. The front 19 of the box portion has a rectangular opening 20 through which the numbers and other markings of the license tag are visible and the numbers and other markings are perforated as shown in Figure 1.

A backing sheet or plate 21 is also placed back of the tag 18 and strip springs 22, which are secured at one end to the back 23 of the box portion, are adapted to engage the rear of the sheet 21 and hold the sheet and tag together and also to hold the tag in abutment with the inner surface of the front 19 at a position surrounding the front opening 20. Thus when the license tag and sheet 21 are inserted through the opening 10, the springs 22 will be placed under tension and as soon as the plate and sheet are released, said springs 22 will move them in the proper position and hold them in said position immediately to the rear of the opening 20. The top 24 of the box portion 8 midway within its width is extended upward to provide a pocket 25; said pocket at its rear being closed by an extension 26 of the back 23 with the exception of a hole 27 through which an electric bulb or lamp 28 can be inserted. The front 19 of the box portion is also extended upward to form the front of the pocket 25 and said upward extension of the front has a lens aperture 29 in which is mounted a lens 30; said aperture also including a groove 31 in which a spring ring 32 can be inserted to hold the lens 30 in place as shown in Figure 3; the arrangement being such that the pocket 25 provides an upper compartment 33 in which the lamp 28 is positioned and the lamp is directly to the rear of the lens 30. Thus, when illuminated, the rays of light from the lamp 30 will pass through the lens; certain of the rays of light passing downward into the compartment 34 of the box portion to the rear of the sheet 21. The sheet 21 is of a color similar to the year color of the license tag; it being noted that various States have different color tags for each year so that the

year of the license can be determined by the color of the light passing through the perforations of the license tag when the device is carried by a vehicle during the night. It will thus be understood that when the device is carried by a vehicle and the lamp 28 is illuminated, a portion of the light will pass out through the lens 30 and a portion of the light will penetrate the perforations of the tag after first passing through the color sheet 21 so that not only will the markings of the tag be displayed but the color of the tag can readily be determined. At the same time the license tag will be securely locked within the case so that it cannot readily be stolen.

The bottom 17 of the box portion 8 has an integral depending hollow extension or pocket 35. The bottom 17 is continued above the top of the pocket 35 to form a partition 36; said partition being interrupted to form a doorway 37 which is adapted to be closed by a door 38 in the form of a detachable plate. The plate 38 has small arms 39 which are secured to ears 40; said ears being cast integral with the partition 36 and having holes through which securing members 41 can be inserted; said securing members also extending through the arms 39. These securing members 41 can be in the form of pins, screws or small bolts so that when the arms 39 are attached to the ears 40, the pocket 35 will be closed and to secure access to the interior of the pocket either of the securing members 41 can be removed and then the door can be lifted on the other securing member as a pivot. If desired both of the securing members 41 can be removed. It will be noted that this action can take place through the medium of the front opening 20 before the license tag is inserted; said opening 20 providing sufficient hand room to allow access to the members 40 and plate 38. The front and rear of the box portion are extended downward to form the front and rear of the pocket 35 and the upper portion of the pocket is made comparatively wide so as to provide a signal sign compartment 42. The lower compartment 43 provided by the pocket 35 is adapted to receive an electric lamp 44 which can be inserted through a hole 45 in the back, and the front of the compartment has a lens aperture 46 in which a lens 47 can be inserted; said aperture 46 also including a groove 48 in which a spring ring 49 can be inserted to retain the lens 47 in place in front of the lamp 44. It will be noted that the compartments 43 and 42 merge one into the other so that a portion of the rays of light from the lamp 44 will pass outward through the lens 47 and another portion of the rays of light will illuminate the compartment 42. The front wall of the pocket 35 within the compartment 42 has integrally cast upwardly extending hook lugs 50 and laterally extending hook lugs 50^a which are immediately adjacent the bottom and side edge walls of a signal sign aperture 51 which is in alignment with the front of the signal sign compartment 42. A signal sign 52 is supported by the lugs 50 and 50^a and can be inserted through the doorway 37. This signal sign 52 is preferably made of opaque material with letters cut therein to form the word "Stop"; the front surface of the signal plate being preferably blackened or darkened so that the perforated letters will stand out prominently and will be visible through the medium of the aperture 51.

A frosted plate 53 of glass or other suitable material is placed to the rear of the signal sign 52 and is also supported by the lugs 50 and 50^a. A strip spring 54 is inserted between the plate 53 and the hooked portions of the lugs so as to firmly press against the plate 53 and hold the sign 52 against the inner surface of the front of the pocket 35 so as to prevent vibration from working the sign loose; it being noted that the spring 54 must be placed in position by slightly bending the same so as to place it under tension.

It will thus be noted that after the license tag has been properly placed within the box portion and the gate 13 locked that access either to the various pockets or the interior of the compartment 34 is prevented so that the interior of the device cannot be tampered with by an unauthorized person; it only being possible to remove the license tag when the gate is removed.

The backing sheet or plate 21 can be made of colored transparent or translucent material, such as glass, celluloid or other suitable material.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A device of the character described including a box portion having a viewing aperture; an opening in said box portion for the insertion of a license tag to be disposed in said box portion and held before said aperture; closure means for said opening; means for locking said closure means in position; integral extensions upon said box portion, said extensions being provided with lenses; and a lamp in rear of each lens colored means disposed in said box portion and used in conjunction with said license tag.

tag; and a partition in said box portion detachably fastened between said box portion and the adjacent extension.

2. A device of the character described including a box portion having a viewing aperture; an opening in said box portion for the insertion of a license tag to be disposed in said box portion and held before said aperture; integral extensions on the top and bottom of the box portion, said extension being provided with lenses, and a lamp in rear of each lens, said box portion and said extension being in communication with each other; a partition arranged to close the communication between said box portion and one extension; there being spaced ears which are pivotally mounted upon said partition; members extending through said ears, said members being detachably connected to said box portion.

3. A device of the character described including a box portion having a viewing aperture; integral extensions on the top and bottom of said box portion provided with lenses and a lamp in rear of each lens; and a partition detachably secured between one of said extensions and said box portion, said partition being arranged in position to be reached through said viewing aperture.

30 4. A device of the character described including a box portion having an opening for the insertion of a license tag; extensions on the top and bottom of the box portion provided with lenses; a lamp in rear of each lens; means for supporting a signal sign in said bottom extension; said means including an opening having spaced lugs disposed

about the same and adapted to receive said sign, and a spring member disposed within said lugs to hold said sign in position. 40

5. A device of the character described including a box portion having an opening for the insertion of a license tag; a colored plate disposed in rear of said license tag, integral extensions on the top and bottom of the box portion, each of said extensions being provided with a lens; a lamp in rear of said lens; means for supporting a signal sign in said lower extension, said means including an opening having spaced lugs disposed about the same and adapted to receive the signal sign, there being a spring member placed within said lugs to hold said sign in position; and a partition detachably fastened between said bottom extension and the 55 interior of said box portion.

6. A device of the character described including a box portion provided with a front opening and an open end and having a channel disposed around the same; a gate 60 sliding in the channel for closing the open end; a flange on the gate having an opening; a lug on the box portion passing through the opening in the flange; a perforated license tag at the front opening, 65 and a lamp within the box portion for illuminating the license tag.

In testimony whereof I have signed my name to this specification in the presence of two subscribing witnesses.

FLOYD BISCH.
